UNITED STATES PATENT OFFICE.

JAMES STEEL AND JOHN MCINNES, OF GLASGOW, NORTH BRITAIN.

IMPROVEMENT IN ATMOSPHERIC CAR-BRAKES.

Specification forming part of Letters Patent No. 155,117, dated September 15, 1874; application filed April 3, 1874.

To all whom it may concern:

Be it known that we, JAMES STEEL and JOHN MCINNES, both of Glasgow, in the county of Lanark, North Britain, engineers, have invented Improved Apparatus for Actuating the Brakes of Railway-Trains by Compressed Air, part or parts of which are also applicable for signaling in railway-trains, of which the following is a specification:

Our invention relates to air-brakes in which a supplementary air-reservoir is combined with each brake-operating piston and cylinder; and our invention consists chiefly of certain passages and devices, described fully hereafter, whereby the air is admitted at equal pressure on both sides of each piston, and the latter is operated by withdrawing the air from either side.

On Sheet 1 of the drawings hereunto appended, Figure 1 is a vertical section of a compressed-air cylinder and receiver, with attachments constructed in accordance with our invention. Fig. 2, Sheet 1, is a vertical section at right angles to Fig. 1, while Fig. 3 is a side elevation thereof.

The cylinder A and air-vessel B are shown formed in one casting. The cylinder A is cast with the upper end close, the lower end being fitted with a cover, C. The cover C is provided with a stuffing-box and gland, D, secured by studs E to the cover C, the space F being filled with any suitable packing. On the inner side of the cover C a hollow cylindrical projection, G, is formed, upon which the piston H rests when in its lowest position—that is to say, when the brakes are off. The projection G is provided at the top with an india-rubber ring, I, which acts as a cushion to prevent any shock which might arise from the fall of the piston H. The space between the piston-rod J and the interior of the cylindrical projection G may be filled with packing to further prevent the escape of air from the cylinder A. The piston H is packed by a cup-leather secured to its upper side by a washer, K, and nut L, which nut L at the same time secures the piston H to the piston-rod J, as shown on the drawings. An india-rubber ring, M, is placed upon the washer K, to cushion the shock in the event of the piston striking against the top of the cylinder.

On the inlet-pipe N is a branch, O, in which is formed a valve chest and seat. The branch O is connected to the air-vessel B by a pipe, P. A ball valve or clack, Q, accurately fitting the seat in the branch O, prevents the air from returning by the valve Q. The piston-rod J is coupled to the brake apparatus by the connecting-links R, which are shown double, (see Fig. 2,) in order that they may clear the drag-hook X'. These links R actuate the lever S, fixed upon the brake-shaft T, which is operated correspondingly with the movement of the piston in the cylinder A. In applying our invention to a vehicle running upon "bogies," the brake-shaft T is connected to the piston-rod J by means of a flexible coupling, such as a chain or connecting-rod fitted with a universal joint, so as to allow for the movement of the body of the carriage upon the swivelpins of the bogies, as hereinafter set forth. The brake-shaft T is carried in brackets U, bolted to the lower frame-work of the carriage. The brake cylinder and receiver are fixed to the lower frame-work and floor of the carriage by bolts V, which pass through a flange formed upon the sides of the air-vessel B. The air-vessel B projects through the end of the carriage, and is situate below the seat Y', as shown in section at Fig. 1, Sheet 1. The coupling, whereby communication is effected between the cylinders on the different carriages, is shown particularly at Figs. 2 and 3, Sheet 1. Openings W are formed at the upper part of the air-cylinder A. Caoutchouc or other elastic rings X fill recesses formed for their reception in the faces Y. To keep the elastic rings X in their places, metallic rings Z are bolted on the faces Y, the interior edges of which rings Z overlap to some extent the elastic rings X, and thus hold them in position. Projections a are formed opposite the faces Y, and then are bushed with screwed nuts b, through which the screws c pass, the centers of which are opposite to the centers of the openings W. The inner extremities of the screws c are provided with anti-friction thimbles d, and the outer extremities with vise-handles e, by which the screws c are actuated. A hollow metallic T-piece is held between the thimble d and the elastic ring X, the pressure imparted by

tightening the screw *c* being sufficient to insure an air-tight joint between the circular flat edge of the hollow metallic **T**-piece and the face of the elastic ring *X*. The junction of the **T**-piece and the flexible tube which connects the cylinders is effected by forming a nozzle or projection, *g*, upon the **T**-piece, over which the flexible tube *h* is drawn, and in which position it is held by a box-nut and thimble-washer, as shown on the drawings. On the other side of the cylinder from that on which the **T**-piece is shown at Fig. 2, Sheet 1, the screw *c* is indicated as advanced inward, so that the thimble *d* presses upon the elastic ring *X*, and closes the opening *W*.

Fig. 4, on Sheet 2, is a side elevation of a locomotive-engine and tender fitted with the necessary apparatus for operating our improved air-brake apparatus. An air-pump, *A*, is shown bolted to the fire-box of the locomotive-boiler, and it is driven by a small steam-engine situate on the other side of the fire-box, (but not seen on the drawings,) which drives the crank-shaft *O*. The air is pumped through the tubing *B* into the tubular receiver *C*. Upon a branch pipe, *D*, projecting from the receiver *C*, is fastened a two-way cock, *E*, by means of which the pressure of air from the receiver *C* may either be directed through the tubing *F* to the cylinders on the carriages, or it may be entirely cut off therefrom or directed into the atmosphere, at pleasure.

Fig. 5, Sheet 3, is a part side elevation and part section of two covered railway-carriages, showing our improved air-brake. Fig. 6 is an end elevation of a similar covered railway-carriage.

As shown at Fig. 5, Sheet 3, the air-cylinders *A* at either end of each carriage are connected in their upper parts at the pipe *N* by the flexible tube *x*. Near one end of the carriage the signaling-whistle *C* is situated. The signaling-whistle *C* may be operated from the interior of the carriage by means of a wire, cord, or chain, (not shown on the drawings,) but which is led along the roof of the carriage and attached to the lower extremity of the lever *c*, fastened to the spindle of the whistle-valve of the signaling apparatus *C*, and which is thus sounded; or the flexible tube *x* may be led into the interior of the carriage, and a cock or valve placed thereon, by operating which the whistle *C* is sounded. The lever *d*, standing at right angles to the lever *c*, carries a counter-weight, which shuts the valve of the whistle *C*, on the pulling strain being removed from the wire, cord, or chain.

The brake-blocks *m*, Sheet 3, are actuated from the piston-rods *J* through the connecting-links *R*, which actuate the levers *S*, fixed upon the brake-shafts *T*. From the brake-shafts *T* the brakes *d* are operated in the ordinary manner by the levers *e* and connecting-rods *f*. The brake-shaft *T* is carried by brackets *U*, bolted to the lower frame-work of the carriage.

The mode of operating our invention is as follows: A sufficient pressure of air having been raised in the receiver *C* by the air-pump *a*, Sheet 2, the two-way cock *E* is opened, allowing the air to travel through the tubing *F* into the air-cylinder on the first carriage, whence it issues through the pipes on the carriage-roof to the air-cylinder at the opposite end of the carriage, and thence, similarly, through the flexible pipes and couplings to the several other cylinders and air apparatus throughout the train. When it is desired to apply the brakes, the air-pressure is removed from above the pistons *H*, (either by the engine-man turning the two-way cock on the engine so as to let off the air above the pistons, or which may be accomplished by a passenger pulling one of the cords, or operating any of the cocks by which the air escapes, to sound the signaling apparatus.) The air confined in the air-vessel *B*, and under part of the cylinder *A*, under pressure then expands and lifts the piston *H*, carrying with it the piston-rods *J* and links *R*, which actuate the levers *S*, and through it the brake-shafts *T*, which operations, as will be seen by reference to Sheet 3, apply the brakes by operating the levers *e* and connecting-rods *f*. To withdraw the brakes the pressure of air is again admitted to the upper part of the cylinder *A*, which throws the pistons *H* into equilibrium, when their own weight and the weight of their attachments, which may or may not be aided by counter-weights or springs, causes the piston to fall to the bottom of the cylinder *A*, and thus withdraw the brakes.

The coupling operation, whereby the air-cylinders on the adjoining carriages or vehicles composing the train are connected, is effected by placing the **T**-piece coupling, Fig. 2, Sheet 1, between the inner extremity of the screw *c* and the face of the elastic rings *X*, and screwing up the coupling firmly in that position by means of the vise-handle. The apparatus for fixing the **T**-piece coupling is placed on both sides of each cylinder *A*, and each cylinder *A* is provided with two flexible tubes and couplings, one or both of which may be used to connect the cylinders of adjoining carriages. When in action the cylinders are coupled together by both flexible pipes; but in uncoupling them for the purpose of disconnecting the carriages, it is necessary only to unscrew one coupling on each carriage, and at the opposite sides of the respective cylinders, so that one of the flexible tubes is left hanging to each cylinder, thus allowing the flexible tubes and couplings always to come together in proper position for being recoupled, whether the same ends of the carriages are brought opposite to each other or not. In the event of a rupture of one of the flexible tubes between the cylinders on adjoining carriages taking place, the coupling-hole on the cylinder may be closed by the thimble on the end of the coupling-screw being pressed into it by the screw and connection maintained by the pipes for operating the

brakes. At the end elevation of the last carriage of a train, shown at Fig. 6, Sheet 3, both of the couplings of one flexible pipe, *f*, are shown applied to the opposite sides of the same air-cylinder, thus closing the openings and preventing the escape of air at the last cylinder, or otherwise the flexible pipes and couplings may be withdrawn, in which case the openings are closed by the thimbles on the ends of the screws *c*.

An important feature of our improved air-brake apparatus is that, as the pressure of air is in constant action throughout the train, it may at any time be instantaneously applied; and in the event of the ordinary screw or chain couplings breaking, so that the train becomes disconnected while running, the air-pressure on the upper side of the pistons being withdrawn by escaping through the broken air-pipes causes the brakes on each section of the broken train to be simultaneously applied, thereby stopping both parts of the train.

Fig. 7, Sheet 4, is a side elevation of a railway-carriage (running on bogies, and having a doorway through each end) to which our invention is shown applied. Fig. 8 is an end elevation of Fig. 1. As the doorway prevents the application of a single cylinder at the center of each end of the carriage, as shown on Sheet 3, two cylinders are used, one at each side of either doorway, each cylinder having

a single instead of a double receptacle for the T-piece coupling hereinbefore described. To allow for the lateral and swiveling motion of the bogies, the connection between the piston-rod and the lever on the brake-shaft is made flexible by either a chain or connecting-rod with a universal joint.

The signaling apparatus shown upon the roof of the carriage is operated from the interior by means of a cord-valve or cock, as hereinbefore described.

I claim—

1. The combination of a cylinder, *A*, an air-reservoir, *B*, communicating therewith, piston to both sides of which air is admitted under pressure, and an outlet in the cylinder through which the air may pass from one side of the piston, all as described.
2. The combination of the cylinder *A*; opening *w*, screw *c* provided with a thimble, *d*, and a pipe having a T-head confined to the mouth of the opening by the screw, as set forth.

In testimony whereof we have signed our names to this specification in the presence of two subscribing witnesses.
